UNITED STATES PATENT OFFICE.

ADOLF FRANKE, OF BERLIN, GERMANY.

MEANS FOR PRODUCING PHASE-SHIFTED OSCILLATIONS IN A PLURALITY OF INDEPENDENT OSCILLATION-CIRCUITS.

1,186,654.

Specification of Letters Patent. Patented June 13, 1916.

Application filed October 1, 1913. Serial No. 792,802.

To all whom it may concern:

Be it known that I, ADOLF FRANKE, a subject of the German Emperor, and residing at Berlin, Germany, have invented certain new and useful Improvements in Means for Producing Phase-Shifted Oscillations in a Plurality of Independent Oscillation-Circuits, of which the following is a full and clear specification.

10 My invention is illustrated in the accompanying drawings and more clearly set forth in the annexed claims.

15 My invention refers to a means by which phase shifted electric oscillations can be set up in a plurality of independent oscillation circuits such as for instance, antenna circuits used for transmitting wireless messages, in order to effect directed transmission of messages.

20 It is well known that a directed radiation can be obtained by using a plurality of transmitters and by feeding to them high frequency currents of the same frequency but different phase. In such an arrange-

25 ment to get an effective directed radiation, it is necessary that the phase difference of the several antenna currents maintain a certain predetermined relation to the distance of the different antennæ from each 30 other and to the frequency or wave-length of the currents used. For a given antenna arrangement this phase difference must have a certain predetermined and constant value. For this reason it is not possible to use for 35 the generation of the high frequency oscillations any device making use of spark gaps because of the uncertain action of such gaps by which the phase relation would constantly be disturbed in an irregular and un-

40 controllable way. In case high frequency generators are used instead of spark gaps, it is possible to produce such oscillations of a very constant and predetermined phase difference. On the other hand as the distance of the antennæ from each other ought 45 not to be small compared with the wave length in order to produce effective radiation, it is necessary to conduct the currents produced by the generator over a consider-

50 able distance. If the frequency used for the radiation is directly produced in the generator, the conduction of these high fre-

quency currents over a considerable distance involves relatively great losses, and serious difficulties in constructing the circuits owing 55 to the fact that the lengths of the leads from the generator to the antennæ are not small compared with the quarter wave lengths. These difficulties are overcome through my invention by making the frequency of the 60 oscillations produced in the generator a sub-multiple of the frequency of the antenna oscillations, and conducting the currents of such relatively low frequency to the transmitting stations where the antennæ are located and multiplying the frequency at the transmitting stations by means of stationary frequency changers to the value of the frequency of the antenna circuits. By this arrangement it is possible to use an appropriate 65 high frequency for the radiation and at the same time a considerably lower frequency at which the currents are generated and conducted to the transmitting 70 station.

75 By producing currents of comparatively low frequency in the generators, which may be of the order of about 10,000 per second, it is possible to regulate the phase of the individual circuits relatively to that in the other circuits in a very exact manner, since by such generation the phase is determined directly by the machine. For instance, in case three circuits are being used, a three-phase alternating current machine may be 80 used, or in case more than three circuits should be energized, also multiple phase generators may be used, or also the currents of the machine may be brought into the proper phase relation to each other by so-called phase-transformers. When using such phase-transformers it is also possible to regulate the phase of the individual currents to control same to the desired nicety.

85 The frequency changers or multiplicators 90 of the character referred to above are known in the art and one form of such devices has been clearly described in a co-pending application of Georg von Arco and Alexander Meissner for means for producing high frequency currents, Serial Number 762,359, filed April 19, 1913.

100 By the arrangement above outlined, it is possible to obtain a more effective directed

wireless telegraphy than was the case heretofore, and in particular such means prove highly satisfactory and to be almost indispensable in high power wireless stations.

In the annexed drawing I have illustrated a number of forms in which my invention may be reduced to practice.

In this drawing,—Figure 1 represents diagrammatically a transmitting system with two transmitter stations supplied by two-phase alternating currents in the primary frequency changer circuit. Fig. 2 represents diagrammatically a transmitting system comprising three transmitter stations supplied by three-phase alternating current in the primary frequency changer circuit. Figs. 3 and 4 represent two different means for shifting the phase of the alternating currents supplied to the several transmitter stations.

In Fig. 1 of the drawings, the two transmitting stations A—A having the antennæ 1—1 are supplied for instance by a two-phase generator 2, which might be located in the main building of the entire station. At each transmitting station A, a frequency changer 3 is arranged consisting of for instance two sets 4 and 5 of transformer couples, each of which has an auxiliary direct current magnetizing circuit 6. Such changers or multipliers are known in the art and the description of their manner of operation has been therefore omitted in the present description. The currents of submultiple frequency generated in the generator 2 are conducted at that frequency through the lines 7—7 to the primary windings 8 of the first set 4. The secondary windings 9 of this set are connected over the tuning means 10 and 11 with the primary windings 12 of the second set 4, whereas the latter's secondary windings 13 are connected in series with the antenna circuit. The latter may be also properly tuned by means of the inductance 14 and the condenser 15. Thus the frequency of the currents supplied to the antennæ is increased by two fold multiplication to four times the frequency. It is obvious that the number of frequency changers arranged in cascades such as is shown in Fig. 1, may be optional and it is possible to choose the primary frequency of the generator so low that the currents generated at such frequency may be conducted through lines 7 practically without material loss, whereas the frequency may be increased by means of the changers shown, to a value suitable for wireless transmission.

If more than two antennæ should be supplied with energy in the manner described, for instance three antennæ arranged in a triangle, a three phase alternating current generator is used which supplies currents to three frequency changer sets, one provided for each antenna. This is shown in Fig. 2.

In this figure three transmitters A with their respective antennæ 1 are shown, arranged in a triangle, whereas the alternating current machine 2 is arranged as three-phase generator. The remainder of the arrangement is substantially the same as in Fig. 1, and indicated by similar reference numerals.

Fig. 3 shows an arrangement for shifting phases directly in the generator, whereas Fig. 4 shows the arrangement for shifting the phases outside of the generator.

In Fig. 3, 16 is the rotor and 17 the stator which consists of two elements electrically separated from each other, each stator element generating one phase. The shifting of phases in this case is effected by angularly shifting one member 17 against the other, for instance by a worm gear 18 as shown in Fig. 3, or other suitable means known in the art.

The shifting of phases may also be brought about in a manner diagrammatically shown in Fig. 4. In this figure it is assumed that the primary generator (not shown) generates a three-phase alternating current which is received over the lines 20, and it is assumed that two antennæ are present to which separate single phase currents of a given phase relation should be supplied in the manner above described. To accomplish this the three phase alternating current is supplied by means of lines 20 in parallel to the stator windings of two three phase alternating current motors or generators which are diagrammatically indicated in Fig. 4 at 19 and 21. 19 are the stators and 21 the rotors. Thus in each stator 19 a rotating field is generated. The rotors of the two motors are prevented from rotation by suitable mechanical means, so that in the winding of the rotors currents are generated whose periodicity is the same as that of the three phase alternating current supplied. On the other hand the phase of the current generated in the windings of each of the rotors 21 depends upon the angular position of the rotor to the stator. In Fig. 4 one winding is diagrammatically shown on each stator 21 and connected to the conductors 7 which lead to the frequency changers shown in Figs. 1 and 2. Each of these windings represents a one phase winding, so that one phase alternating current is generated therein. If now the two rotors are set so relatively to their respective stators that the planes through the two windings are at the same angular position, relatively to the stators, the currents supplied to lines 7 have no difference in phase. On the other hand, if one rotor is angularly shifted relatively to the other, the degree of phase shifting between the currents generated in the two rotors depends upon the value of the angle at which the rotors stand, relatively to each other. Therefore, according to the angular

position of the two rotors any desired phase shifting of the currents in the two antennæ, relatively to each other, may be obtained.

I claim:

- 5 1. Arrangement for producing phase shifted sustained oscillations of the character described comprising a plurality of transmitters having antenna circuits, each of the same frequency and separated by a substantial distance, an alternating current generator having a frequency substantially equal to a submultiple of the antenna frequency and adapted to produce currents of different phase, means for conducting said 10 phase shifted currents, one phase to each transmitter and means at each transmitter for multiplying the frequency of said currents substantially to the value of the antenna circuit frequency before they are supplied to the antenna circuit.
- 15 2. Arrangement for producing phase shifted sustained oscillations of the character described, comprising a plurality of transmitters having antenna circuits, each 20 of the same frequency, an alternating current generator having a frequency substantially equal to a submultiple of the antenna frequency, means for varying the phase relation of the currents produced by said generator, means for conducting said phase shifted currents, one phase to each transmitter and means at each transmitter for multiplying the frequency of said currents 25 substantially to the value of the antenna circuit frequency before they are supplied to the antenna circuits.
- 30 3. Arrangement for producing phase shifted sustained oscillations of the character described comprising a plurality of transmitters having antenna circuits, each 35 of the same frequency and separated by a substantial distance, an alternating current generator having a frequency substantially equal to a submultiple of the antenna frequency, means for varying the phase relation of the currents produced by said generator, means for conducting said phase shifted currents, one phase to each transmitter and means at each transmitter for multiplying the frequency of said currents substantially to the value of the antenna circuit frequency before they are supplied to the antenna circuits.

- 35 3. Arrangement for producing phase

shifted sustained oscillations of the character described, comprising a plurality of transmitters having antenna circuits, each 40 of the same frequency and separated by a substantial distance, an alternating current generator having a frequency substantially equal to a submultiple of the antenna frequency, means for varying the phase relation of the currents produced by said generator, means for conducting said phase shifted currents, one phase to each transmitter and stationary frequency changers at each transmitter for multiplying the frequency 45 of said currents substantially to the value of the antenna circuit frequency before they are supplied to the antenna circuits.

4. Arrangement for producing phase shifted sustained oscillations of the character described, comprising a plurality of transmitters having antenna circuits, each 50 of the same frequency and separated by a substantial distance, an alternating current generator having a frequency substantially 55 equal to a submultiple of the antenna frequency, phase shifting transformers for varying the phase relation of the currents produced by said generator, means for conducting said phase shifted currents, one 60 phase to each transmitter and means at each transmitter for multiplying the frequency of said currents substantially to the value of the antenna circuit frequency before they are supplied to the antenna circuits.

ADOLF FRANKE.
